The ornamental design for a garment, as shown and described.

DESCRIPTION

FIG. 1 is a front view of a garment that is in an in-use configuration showing the present design; FIG. 2 is a front view of the garment of FIG. 1, wherein the jacket is in a laid-flat configuration; and FIG. 3 is a back view of the garment of FIG. 2; and, FIG. 4 is a magnified view of the area indicated in FIG. 1. The broken lines with alternating dashes and dots, immediately adjacent to the shaded area, represent unclaimed boundaries of the design. The unshaded regions, demarcated by broken lines, represent unclaimed portions of the garment and form no part of the claimed design. The broken lines, which include even-length segments, that show the remainder of the garment or that are within the shaded area, are for environmental purposes only and form no part of the claimed design. The broken lines comprising an alternating pattern of two dashes separated by a dot are used to indicate the boundaries of a magnified view as shown in FIG. 4 and form no part of the claimed design. The contrast shading on the claimed portion is provided only to indicate the character and/or any contour or curvature of the surfaces. It does not indicate color, texture, markings that actually exist thereon, indicia, graphic representations, surface treatment, or any other ornamentation applied to the article.
